CLAIM

The ornamental design for an illuminated belt, as shown.

DESCRIPTION

FIG. 1 is a rear perspective view of an illuminated belt showing our new design;

FIG. 2 is a front perspective view thereof;

FIG. 3 is a top plan view thereof in an unfastened position;

FIG. 4 is a front elevational view thereof;

FIG. 5 is a rear elevational view thereof;

FIG. 6 is an end elevational view thereof;

FIG. 7 is an opposite end elevational view thereof; and,

FIG. 8 is a bottom plan view thereof.
